CHEMICAL TOILET

Filed April 16, 1928

UNITED STATES PATENT OFFICE.

CHARLES L. CARPENTER AND WILLARD E. JAQUITH, OF SYRACUSE, NEW YORK.

CHEMICAL TOILET.

Application filed April 16, 1923. Serial No. 270,407.

This invention relates to a chemical toilet for use in homes, schools, factories and other buildings or places where such an equipment may be necessary or desirable 5 and involves the use of a receiving tank or receptacle adapted to be installed in the ground, mainly below the surface thereof and provided with means for receiving a suitable drop tube to which the closet bowl 10 is operatively connected, the tank being provided with a suitable outlet leading to a subsurface hygienic drain pool or other repository.

The main object is to provide a more sanitary and convenient apparatus of this character than has heretofore been practised by constructing the tank and all parts carried thereby or therein as a unitary article of manufacture exclusive of the bowl in such 20 manner that the liquid therein will automatically seal all of the inlet openings leading thereto to prevent the escape of vitiated air and gases therefrom.

Another object is to provide overflow 25 means communicating with the outlet of the tank for automatically regulating the level of the liquid in said tank.

A further object is to provide the overflow tube or baffle with a suitable valve controlling the outlet in the bottom of the tank 30 and to enable the overflow tube with the valve thereon to be raised and lowered for opening and closing the outlet when desired.

Another object is to provide the top of 35 the tank with a manhole tube rigidly secured thereto to form a gas and liquid tight joint therewith and adapted to extend upwardly therefrom above the surface of the ground and also into the tank below the normal level of the upper end of the overflow tube so that the liquid will seal the opening 40 in the lower end of the manhole tube around the upper end of the overflow tube.

Another object is to provide movable 45 means within the manhole tube and operatively connected to the overflow tube for raising and lowering the latter and the valve carried thereby to open and close the outlet in the bottom of the tank at will.

Another object is to provide the interior 50 of the tank with an agitator having a stem extending upwardly through a tubular guide in the tube of the tank where it is accessible for operation at will and to extend the guide tube into the tank below the level of the

liquid therein so that the liquid may form a gas tight joint therewith.

A further object is to provide the top of the tank with a guide tube secured thereto to form a liquid-tight joint therewith for receiving the lower end of the drop tube leading from the closet bowl and to extend the tubular guide below the level of the liquid in the tank so that the liquid may form a seal therewith to prevent the escape of vitiated air or gas through the drop tube.

Other objects and uses relating to specific parts of the apparatus will be brought out in the following description.

In the drawings:—

Figure 1 is a longitudinal vertical sectional view of a chemical toilet apparatus involving the various features of our invention.

Figure 2 is an enlarged horizontal sectional view inverted through the upper end of the manhole tube taken on line 2—2, Figure 1, showing the operating means for the overflow tube and valve carried thereby.

As illustrated, this apparatus comprises 80 a horizontally elongated tank or receptacle —1— adapted to be installed mainly beneath the surface of the ground —A— so as to extend partially at the outside and partially at the inside of a building wall —B—.

The inner end of the tank is provided with a tubular guide —2— secured in an opening in the top wall thereof to form a liquid-tight joint therewith and extended some distance above and below said top wall 90 for receiving an upwardly extending drop tube —3— which is also secured in an opening in the upper end of the guide tube —2— to form an air and gas tight joint therewith.

This drop tube —3— extends a relatively short distance below the upper end of the guide tube —2— and also extends upwardly to a superposed floor —F— upon which is mounted a closet bowl —C— having its 100 lower end connected to the upper end of the drop tube in any well-known manner to form an air and gas tight joint therewith.

The outer end of the tank is provided with a manhole tube —4— which is secured in an opening in the top wall thereof to form a gas tight joint therewith and has its upper end extended above the ground line —A— and its lower end extended slightly below the normal level —1'— of the liquid in the tank, 110

as determined by a suitable overflow tube, presently described.

In like manner the lower end of the drop tube extension —2— extends below the normal level of the liquid in the tank to form a liquid-seal therewith.

The bottom of the outer end of the tank —1— is provided with an outlet tube —5— having its upper end extended slightly above said bottom to form a valve seat for the overflow tube and its lower end extended below the bottom of the tank for connection with a suitable drain pipe —6— adapted to be connected to a subsurface drain pool —7—, as shown in Figure 1.

The outlet through the tube —5— is controlled by a valve —8— which is secured to the lower end of an overflow tube —9— and is normally closed by its own weight and by the weight of the overflow tube —5— but may be opened at will in a manner presently described.

The outlet tube —5— and overflow tube —9— are arranged in vertical alignment with the interior of the manhole tube —4—. The upper end of the overflow tube —9— terminates some distance below the top of the tank —1— but above the lower end of the manhole tube —4— when the overflow tube is in its lowermost position to close the valve —8— thereby determining the level of the liquid within the tank.

An operating rod or stem —10— is extended centrally through the overflow tube —9— and has its lower end pivotally connected by a pin —11— to the corresponding end of said overflow tube and its upper end extended into the manhole tube —4— and pivotally connected at —12— to a cross bar —13—.

This cross bar —13— extends diametrically across the interior of the upper end of the manhole tube —4— and is removably and pivotally attached at both ends to suitable brackets —14— on adjacent sides of the manhole tube —4— by means of pivotal pins —15—.

The brackets —14— are secured to the inner sides of the manhole tube —4— and are provided with a series of apertures arranged in planes one above the other for receiving the pins —15— and thus permitting the overflow tube —9— and its valve —8— to be adjusted vertically to different positions as may be required to firmly close the valve —8— upon its seat.

The upper end of the manhole tube —4— is normally closed by a cover or cap plate —16— which is held in place by nuts —17— and bolts —18—, the latter being secured to diametrically opposite sides of the manhole tube —4— at right angles to the bar —13— to extend through registering apertures in the cap plate —16— where they are engaged

by the nuts —17— to lock the cap plate in its closed position and also to permit the removal thereof when it is desired to gain access to the interior of the vat.

When the cap plate —16— is removed one or the other or both of the pins —15— may be withdrawn by hand to permit upward movement of the bar —13— for raising the overflow tube —9— and thereby opening the valve —8— to allow the discharge of the material from the interior of the tank through the outlet —5— and thence to the drain pool, it being understood that the return of the bar —13— to its normal position will automatically lower the tube —9— and close the valve —8—.

The material deposited within the tank —1— may be agitated and thereby more or less liquefied by means of an agitator plate —19— having an operating rod —20— extending upwardly therefrom through a guide tube —21— in the top of the tank —1— and also through an opening in the floor —F— adjacent the bowl —C— where it is provided with a handle —20'— for reciprocating the agitator —19— vertically. The guide tube —21— is secured in an opening in the top wall of the tank to form a gas-tight joint therewith and has its lower end extended slightly below the level of the liquid in the tank to form a liquid seal.

The upper end of the guide tube —21— extends some distance above the top of the tank and is provided with a suitable gland —22— for guiding the rod —20— in its vertical movement and incidentally forming a gas-tight joint therewith.

It will be seen from the foregoing description that the lower ends of each of the tubes —2—, —4— and —21— extend below the normal level of the top of the overflow tube —9— and, therefore, below the normal level of the liquid in the tank so that the liquid may seal the open lower ends of said tubes to prevent the escape of vitiated air or gas therethrough.

Whenever necessary or desirable the agitator —19— may be reciprocated vertically by means of its operating rod —20— for liquefying the solids in the tank and permitting them to flow off through the overflow tube —9— and thence outwardly through the drainage pipe —6— as soon as the level of the liquid rises to the level of the tube of the overflow tube.

Whenever it is necessary or desirable to drain the tank the cap plate —16— may be removed thus permitting access to the bar —13— and its retaining pins 15, either of which latter may be withdrawn to permit the bar to be rocked upwardly about the other pivotal pin to raise the overflow tube —9— and thereby open the valve —8— for drainage purposes.

It will be noted that the manhole tube

—4— is of sufficient interior diameter to permit the overflow tube —9— and parts carried thereby to be withdrawn upwardly through the manhole tube to the exterior of 5 the tank for repairs or replacements when desired.

What we claim is:—

1. In a chemical toilet, a receiving tank having a drainage outlet, an overflow tube 10 within the tank communicating with the outlet for determining the level of the liquid in the tank, a toilet bowl above the tank, a drop tube leading from the lower end of the bowl and provided with an extension tube 15 secured in an opening in the top of the tank and having its lower end extending slightly below the liquid level in the tank to form a liquid seal, a valve on the overflow tube controlling said outlet, said overflow tube 20 being movable vertically to open and close the valve, a guide tube secured in an opening in the top of the tank and having its lower end projecting slightly below the level of the liquid in the tank to form a liquid 25 seal therewith, and an agitator reciprocally movable within the tank and provided with an operating rod extending through said guide tube and adapted to be operated by hand for reciprocating the agitator.
2. In a chemical toilet, a receiving tank having a drainage outlet, an overflow tube 30 within the tank communicating with the outlet for determining the level of the liquid in the tank, a toilet bowl above the tank, a drop tube leading from the lower end of the bowl and provided with an extension tube 35 secured in an opening in the top of the tank and having its lower end extending slightly below the liquid level in the tank to form a liquid seal, a valve on the overflow tube 40 controlling said outlet, said overflow tube being movable vertically to open and close the valve, a manhole tube secured in an opening in the top of the tank in vertical 45 alinement with the overflow tube and extended slightly below the level of the liquid in the tank to form a liquid seal therewith, and a cover removably secured to the upper end of the manhole tube.

3. In a chemical toilet, a receiving tank 50 having a drainage outlet, an overflow tube within the tank communicating with the outlet for determining the level of the liquid in the tank, a toilet bowl above the tank, a drop tube leading from the lower end of the bowl and provided with an extension tube 55 secured in an opening in the top of the tank and having its lower end extending slightly below the liquid level in the tank to form a liquid seal, a valve on the overflow tube 60 controlling said outlet, said overflow tube being movable vertically to open and close the valve, a manhole tube secured in an opening in the top of the tank in vertical alinement with the overflow tube and ex- 65 tended slightly below the level of the liquid in the tank to form a liquid seal therewith, a cover removably secured to the upper end of the manhole tube, and movable means mounted in the manhole tube and opera- 70 tively connected to the overflow tube for moving the same vertically to open and close the valve.

4. In a chemical toilet, a receiving tank having an outlet in the bottom thereof, an 75 overflow tube communicating with said outlet and having its upper end disposed at a predetermined level within the tank, a valve on the overflow tube controlling said outlet, a manhole tube secured in an opening in 80 the top of the tank and having its lower end surrounding the upper end of the overflow tube and extending below the level of the upper end thereof, a cover plate removably mounted on the upper end of the manhole 85 tube, and means for raising and lowering the overflow tube to open and close the valve, in combination with a toilet bowl supported in a plane above the tank, and a drop tube leading downwardly from the bowl and 90 secured in an opening in the top of the tank, said drop tube having its lower end disposed in a plane below the level of the top of the overflow tube.

In witness whereof we have hereunto set 95 our hands this 20th day of March, 1928.

CHARLES L. CARPENTER.
